Patented July 15, 1919.

UNITED STATES PATENT OFFICE.

WALTER G. BONNER, OF PEPPERWOOD, CALIFORNIA.

RACK.

1,309,608.

Specification of Letters Patent. Patented July 15, 1919.

Application filed February 23, 1917. Serial No. 150,524.

To all whom it may concern:

Be it known that I, WALTER G. BONNER, a citizen of the United States, and a resident of Pepperwood, in the county of Humboldt and State of California, have invented 5 a certain new and useful Improvement in Racks, of which the following is a specification.

The present invention relates to racks, 10 more particularly adapted for use in the kitchen for holding pot lids, covers and the like.

An object of the present invention is to provide a rack of this nature which is of 15 relatively simple construction, which may be economically formed from wire, which may be easily and quickly secured against the wall or the like in any desired or convenient place, and which is foldable to lie 20 flat against the wall when not in use, and to occupy relatively small space when packed away, and when transported in large quantities.

Another object of the present invention 25 is to provide a wire rack of this nature which is so peculiarly constructed that the lengths of wire used interbrace one another and provide a firm, solid support by the use of relatively thin wire.

The invention further aims at the provision of a rack of this nature which is adapted 30 to support a relatively large number of lids or covers, and which holds the same in upright and spaced-apart relation so that access 35 may be readily had to any one of the lids or covers without disturbing the remaining articles supported on the rack.

The above, and various other objects and advantages of this invention will be in part 40 described, and in part understood, from the following detailed description of the present preferred embodiment, the same being illustrated in the accompanying drawing wherein:—

Figure 1 is a perspective view of a rack 45 constructed according to the present invention, showing the same mounted against a wall and having a cover supported upon the same.

Fig. 2 is a vertical section taken substantially centrally through the same.

Fig. 3 is a plan view of the rack folded and detached from the wall.

Referring to this drawing, the rack comprises a body frame formed of a relatively 55 fixed part 10, and a hinged or movable part 11.

The fixed part 10 comprises a single length of wire which is provided midway between its ends with a loop 12 adapted to extend upwardly when the rack is in position against the wall, and provided near its opposite ends with loops 13 extending in the same plane as that of the loop 12. The opposite extremities of the part or wire 10 are looped 60 to provide hinge eyes 14 which extend substantially in parallelism and outwardly from the ends of the fixed part 10.

The hinged part of the body frame is in the form of a length of wire which is curved 70 throughout its length, and provided at its opposite ends with overturned eyes or loops 15 for hinged engagement with the eyes 14. The hinged part or wire 11 is provided with a plurality of suitably spaced-apart rods 16 75 which extend transversely across the hinged part and have their opposite ends looped over the adjacent portions thereof, as at 17.

To suitably brace the hinged part 11 upon the fixed part 10, and also to suitably space 80 apart the transverse rods 16, a spacing rod 18, in the form of a length of wire, is looped at one end, as at 19, about the length of wire 11 midway between the ends thereof, and is provided with a loop 20 at its opposite extremity which hingedly engages in an offset 85 loop 21 formed at the base of the loop 12. This spacing rod 18 is provided intermediate its ends with a plurality of suitably spaced-apart eyes or loops 22 through which 90 the transverse bars or rods 16 are threaded to hold the latter in suitably spaced-apart relation and prevent their shifting upon the hinged part of the body frame.

The adjustable or hinged part of the body 95 frame is provided with a brace 23 in the form of a single length of wire which is bent substantially U-shaped and provided upon its free end with loops 24 hingedly engaging about the wire 11 between the ends of a 100 pair of adjacent transverse rods 16. These loops or eyes 24 admit the folding of the

brace 23 flat against the underside of the body frame to collapse the same for storage in a relatively small space, or for convenience in packing and shipment.

5 The brace 23 is provided with a foot-piece 25 in the form of a single length of wire which is rolled over at its opposite ends to provide attaching eyes or loops 26 adapted to receive screws 27 or the like therethrough 10 for securing the foot-piece 25 against the wall. The intermediate portion of the foot-piece 25 is arched or bowed upwardly and is curved laterally so as to approach the outer face of the wall when the foot-piece 15 is secured thereto. This upwardly arched portion of the foot-piece provides a spring-tongue beneath which the free closed end 28 of the brace 23 is adapted to be sprung. When in use, the fixed part 10 of the body 20 frame is secured rigidly against the wall A or the like by screws 29 which are secured through the loops 12 and 13. The hinged part 11 is then free to swing into various angles toward and from the wall, and is held 25 in an outwardly extended position by means of the brace 23 which is engaged at its lower closed end 28 beneath the spring foot-piece 25. The foot-piece 25 may be secured at any desired height upon the wall to dispose the 30 frame 11 at the required angle. The lids or covers B are inserted edgewise between the transverse rods 16, and the handles or knobs C thereof are adapted to engage the adjacent rods 16 and hold the covers or lids B from 35 falling through the rack.

The lids or covers B are thus held separated from each other, and may be individually withdrawn from the rack without disturbing the position of the remaining covers 40 or lids. The foot-piece 25 is of the spring type, as above described for the purpose of preventing the brace 23 from lifting out of the foot-piece to release the hinged part of the body frame. Thus, when the covers or 45 lids B are drawn upwardly there is no danger of disengaging the brace 23 from the foot-piece and thus collapsing the rack.

When it is desired to collapse the rack 50 against the wall it is only necessary to lift the hinged part 11 of the frame sufficiently to force the closed end 28 from beneath the spring-foot 25, when the brace 23 is permitted to swing outwardly and the hinged part 11 of the frame together with the brace may then 55 be folded flat against the wall A.

It is of course understood that various changes and modifications may be made in the details of construction of the above specifically described rack without departing 60 from the spirit of the invention, and being restricted only by the scope of the following claims.

I claim:

1. In a rack, the combination of a two-

part hingedly connected wire frame, one part 65 being provided with loops intermediate its ends adapted for securement against a fixed support, said second frame part being extended outwardly from the first part, a plurality of transversely extending bars 70 secured across said second part, a spacing rod hingedly connected to the first part at one end and engaging the second part at its opposite end, said spacing rod provided with a plurality of intermediately 75 spaced apart loops engaging about said transverse rods to hold them in spaced relation.

2. In a rack, a two-part hingedly connected frame, means for securing one part to a stationary frame, means for supporting the other part in an extended position comprising a frame hingedly connected to the extended part and extending downwardly therefrom, said brace provided with a substantially 85 horizontal portion at its lower end, and a spring foot adapted for securement against said support and provided with an upwardly extending resilient portion adapted to be snapped about the horizontal portion of said 90 brace to yieldably hold the same against said support and prevent the accidental displacement of the brace.

3. In a rack, the combination of a length of wire provided with attaching loops at 95 spaced-apart points throughout its length for securement to a fixed support, a curved length of wire hingedly connected at its opposite ends to the extremities of said first wire, a plurality of spaced apart rods secured transversely across said curved wire and providing parallelly arranged spaces therebetween, and a spacing rod hingedly connected to the intermediate portion of said first length of wire and having engagement 105 at its opposite extremity with the curved wire, said spacing rod having a plurality of spaced-apart loops intermediate its ends through which said transverse rods are threaded for holding the same in spaced- 110 apart relation, and means for supporting said curved wire in outwardly extended position.

4. In a rack, the combination of a two-part hingedly connected wire frame, one 115 part being provided with loops intermediate its ends adapted for securement against a fixed support, said second frame part being extended outwardly from the first part, a plurality of transversely extending bars 120 secured across said second part, a spacing rod hingedly connected to the first part at one end and engaging the second part at its opposite end and provided with a plurality of intermediately spaced apart loops engaging 125 about said transverse rods to hold the same in spaced-apart relation, a brace hingedly connected to said second part and extending

downwardly therefrom and provided with a substantially horizontal portion at its lower end, and a spring foot adapted for securement against said support and provided with an upwardly extending resilient portion adapted to be snapped about the hori-

zontal portion of said brace to yieldingly hold the same against said support and prevent the accidental displacement of the brace.

WALTER G. BONNER.
